UNITED STATES PATENT OFFICE.

JUSTICE H. CLEAR AND FRANCES CLEAR RICHLVILLE, OF CLARKSTON, WASHINGTON.

CHILD'S BOOT.

1,189,665.

Specification of Letters Patent.

Patented July 4, 1916.

Application filed April 12, 1915. Serial No. 20,818.

To all whom it may concern:

Be it known that we, JUSTICE H. CLEAR and FRANCES CLEAR RICHLVILLE, citizens of the United States, residing at Clarkston, in 5 the county of Asotin and State of Washington, have invented certain new and useful Improvements in Children's Boots, of which the following is a specification.

This invention relates to footwear and 10 more particularly to a creeping boot for children, the object of the invention being to provide a boot which may be put on over the ordinary stockings and which will serve not only as a means for preventing the stockings being torn or worn through, but also as 15 a protective covering to prevent injury to the child's limbs, such as might be occasioned by splinters.

The article embodying the present invention is, as will be understood from the foregoing, designed primarily for use by children just learning to crawl and the article is not intended, nor is it adapted for use, as a walking or outdoor boot, its sole purpose being to protect the ordinary stockings 25 and the child's limbs.

It is another aim of the invention to provide an article of footwear of the type mentioned which will be comfortable and yet 30 sufficiently heavy to protect the child's limbs from drafts, and further to so construct the article that it may be readily applied and removed although not liable to become accidentally displaced after application.

35 In the accompanying drawings: Figure 1 is a perspective view, illustrating the manner in which the article is to be worn; Fig. 2 is a perspective view of the article; Fig. 3 is a vertical front to rear sectional view therethrough.

Corresponding and like parts are referred to in the following description and indicated in all the views of the drawings by the same reference characters.

40 The creeping boot embodying the present

invention includes a foot portion having a flexible vamp 1, of leather or other suitable material, a flexible counter or heel portion 2, preferably of the same material, and a flexible sole 3 which is also preferably of the same material. Each of the portions 1, 2 and 3 is formed from a one-piece blank and the blanks are assembled and stitched in the manner clearly illustrated in the drawings. The article further includes a legging portion 4 which is preferably of heavy canvas or duck, although any other suitable cloth material may be used if found desirable. The legging portion 4 is permanently connected at its lower end within the counter 50 and vamp portions of the foot of the article and the said legging portion, at its forward side, is considerably higher than at its rear side so that the upper front portion thereof, indicated at 5, will serve effectually as a 55 covering for the child's knees, thereby affording protection to the child's stockings and also protection against splinters. The rear portion of the legging 4 being terminated, at its upper end, a considerable distance below the upper edge of the forward portion of the legging, the article will not bind the limbs, but will be comfortable to wear and permit entire freedom of movement.

75 In order that the article may be supported in place, it is provided with two supporting straps 6 which are preferably of elastic and which are secured at their lower ends at opposite sides of the portion 5 at the upper 80 edge of the legging. The straps 6 are led upwardly toward each other and have their upper ends united, as at 7, a small loop 8 being formed, through which may be inserted the bar of a safety pin 9 or the corresponding part of any other suitable attaching element or device.

85 Having thus described the invention, what is claimed as new is:

90 A creeping boot for children comprising

a foot portion of leather or other material possessing a similar degree of flexibility and toughness, and a legging portion of flexible material secured at its lower end
5 to the foot portion, the legging portion at the top and rear being located a considerable distance below the top and front of said portion, suspension straps secured at their lower ends at opposite sides of the middle front of the legging portion at the top thereof, and an attaching member connected

to the upper ends of the said suspension straps.

In testimony whereof we affix our signatures in presence of two witnesses.

JUSTICE H. CLEAR.

FRANCES CLEAR RICHVILLE.
